SAMUEL SOSS, OF NEW YORK, N. Y.

HINGE.

1,078,703.

Specification of Letters Patent. Patented Nov. 18, 1913.

Application filed March 1, 1913. Serial No. 751,397.

To all whom it may concern:

Be it known that we, CHARLES J. Soss and HENRY Soss, citizens of the United States, and residing at New York, in the county of New York and State of New York, have invented certain new and useful Improvements in Hinges, of which the following is a specification, such as will enable those skilled in the art to which it appertains to make and use the same.

This invention relates to hinges and particularly to what are known as invisible hinges, and the object thereof is to provide an improved device of this class which may be used in connection with doors sashes or similar constructions involving a swinging member of any kind or class, but which is particularly designed for use in connection with the doors of automobiles and similar vehicles in order to facilitate the disconnection of a door from the frame thereof without detaching the separate parts of the hinge from the door and the frame, a further object being to provide a hinge of the class specified which will hold the door or swinging member against either vertical or lateral movement when said door or member is closed, but which will permit the free and easy movement or swinging of the door in the operation of opening it; and with these and other objects in view the invention consists in a hinge of the class specified constructed as hereinafter described and claimed.

The invention is fully disclosed in the following specification of which the accompanying drawing forms a part, in which the separate parts of our invention are designated by suitable reference characters in each of the views, and in which:

Figure 1 is a view of our complete hinge and showing the parts in the position they occupy when the door or swinging member to which they are secured is fully opened; Fig. 2 a section on the line 2—2 of Fig. 1; Fig. 3 a section on the line 3—3 of Fig. 2 and showing the hinge secured to the door frame and door and showing the door open; Fig. 4 a view similar to Fig. 3 but showing the door closed; Fig. 5 a section on the line 5—5 of Fig. 3, and; Fig. 6 a view similar to Fig. 3 but omitting the door frame and door and showing a modification.

In Figs. 3 and 4 of the accompanying drawing, we have shown at *a* that part of a door frame to which the door is hinged, and at *b* a part of the door, and in the practice of our invention, we provide a hinge comprising three parts *c*, *d* and *e*, the first of which is adapted to be secured to or in the door frame, and the second to the door, while the part *e* is secured, in practice, to the part *c* and is detachable with the part *c* when it is desired to detach the door from the frame.

The part *c* consists of the ordinary hinge butt plate provided centrally of its back with a rectangular casing *c*² which may be secured thereto or cast integrally therewith, and which is adapted to be countersunk in the door frame, as clearly shown in Figs. 3 and 4, and in the top and bottom portions of which are plate members *c*³ which may be secured in the casing *c*², or be cast integrally therewith, and these plates are provided in their inner surfaces with arc-shaped grooves *c*⁴.

The front of the casing *c*² is open and the front ends of the grooves *c*⁴ are also open, as shown at *c*⁵, before the part *e* of the hinge is secured to the part *c*.

The part *d* of the hinge involves an ordinary hinge butt plate *d*² which is secured to the door and the face of which is provided with a curved arm *d*³ which is oblong and rectangular in cross section and which is provided at its outer end with a radial and inwardly directed member *d*⁴ of the same form and dimensions in cross section as the arm *d*³.

The part *e* consists of a plate which is secured to the butt plate *c* and which closes the front of the casing *c*², and the ends of which are countersunk in the face of the butt plate *c*, as shown at *e*², and its connection is made by means of screws *e*³ the heads of which are countersunk in the ends of the plate *c* and the back of the plate *c* is provided with arms *e*⁴ consisting of plates which correspond with the plates *c*³ in the end portion of the casing *c*², and the arms *e*⁴ are insertible into the casing *c*² and removable therefrom with the plate *e*, and the member *d*⁴ of the arm *d*³ which is connected with the plate *d*² is pivoted between the arms *e*⁴ by means of a pivot pin *e*⁵ passed through

the arms e^4 and through the end of the member d^4 , and the ends of the pivot pin e^5 are riveted in the arms e^4 .

The plate e is of less transverse dimensions than the hinge butt plate c to which it is secured, but on the side of the door frame in the direction of which the door swings the edge of the plate e is flush with the corresponding edge of the butt plate c , and the opposite edge of the plate e is provided with an oblong rectangular recess e^6 through which the arm d^3 is free to swing, and the elbow d^5 of the arm d^3 and member d^4 is provided with pins d^6 which, when the plate e is secured to and in the face of the butt plate c , pass into the grooves c^4 and are free to move through said grooves as the door is operated or opened and closed. With this construction, the end portions of the plate e which are countersunk in the face of the butt plate c close or cover the ends of the grooves c^4 when the parts of the hinge are in position for use, and the position of these grooves are indicated in dotted lines in Fig. 1, as are also the position of the arms e^4 which are connected with the plate e which is detachable from the part of the hinge which is secured to, or in, the door frame when it is desired to detach the door from said frame.

The construction shown in Fig. 6 is the same as the construction shown in Figs. 1 to 5, except, that the grooves c^4 instead of being formed in the parts c^3 which, in effect, constitute a part of the ends of the casing c^2 , are formed in the top and bottom faces of the arm d^3 , as shown at c^6 , and the pins d^6 are secured in the top and bottom of the casing c^2 or in the plates c^3 which form a part thereof. With this construction, as will be seen, the part d of the hinge, the arm d^3 and its member d^4 are pivoted to the arms e^4 , which are connected with the plate e , and the door may be detached from the door frame by simply taking out the screws e^3 and lifting or moving the plate e and its connected parts out of the casing c^2 ; and said door may be replaced in position, or in connection with the frame, by simply inserting the arms e^4 and the plate e into position and securing them by means of the screws e^3 . This will be a great advantage, especially when our improved hinge or hinges are used in connection with the door of an automobile or similar vehicle, and the casing c^2 which includes the movable parts of the hinge will also be of great advantage by reason of the fact that it will exclude water from the door frame or the material thereof in the operation of washing or cleaning the door and door frame.

We are aware that a hinge composed of separate parts adapted to be connected with the door frame and door and having an arm similar to the arm d^3

and the member d^4 is broadly speaking, old, but our improvement consists in providing grooves c^4 in the top and bottom of the casing c^2 , and the pins d^6 movable in said grooves, or the corresponding construction shown in Fig. 6, together with the arms e^4 connected with, or forming a part of, the plate e , and the part c^3 of the casing c in which the grooves c^4 are formed, in the construction shown in Figs. 1 to 5 inclusive, 70 or the corresponding construction shown in Fig. 6. With this form of construction the pins d^6 operating in the grooves c^4 , or in the grooves c^6 , form guides for the arm d^3 and hold said arm against vertical or lateral 80 movement of any kind and against any movement at all, except the swinging movement necessary in opening or closing the door, and this prevents the sagging of the door and holds it in proper operative position at all times. The pins d^6 also operate to lock the door against any movement away from the door frame, when said door is in the closed position or in the position shown in Fig. 4, it being evident that in this position of the parts of the hinge, there can be no movement of the door except a movement into the position shown in Fig. 3. It will also be seen that when the door is completely open, the casing c^2 is entirely 90 closed and nothing can be seen except the butt plate c , that part of the hinge which is secured to or in the door frame, the plate e and the arm d^3 of that part of the hinge which is secured to the door, and when the 100 door is closed, the hinge is entirely concealed, or in other words, is invisible. It must be understood however, that our invention is not limited to the closed casing c^2 connected with and forming a part of the 105 hinge butt plate c , as any suitable support may be provided in connection with said butt plate for the part c^3 in which the grooves c^4 are formed, in the construction shown in Figs. 1 to 5 inclusive, or for the pins d^6 in the construction shown in Fig. 6. It must also be understood that the construction shown in Fig. 6 will not lock the door when closed against tendency to move away 110 from the frame but for all other purposes it will work the same as the construction shown in Figs. 1 to 5 inclusive; and although we have described the parts c^3 in the construction shown in Figs. 1 to 5 inclusive as provided with grooves c^4 in which the pins d^6 move, it must be understood that these grooves are not absolutely essential as a convex inner bearing or surface of any kind formed in connection with or attached to the casing c^2 over which the pins d^6 would move in the operation of opening and closing the door would accomplish the same result as the groove c^4 or, in other words, the inner walls of these grooves are the operative parts thereof. 115 120 125 130

Having fully described our invention what we claim as new and desire to secure by Letters Patent is;—

1. A hinge comprising a closed casing adapted to be countersunk in a door frame and provided with a face opening, a part adapted to be secured to a door, and a part adapted to be secured to said casing and to close the face opening therein, said last named part being provided with members which extend into said casing, and the part which is adapted to be secured to the door being provided with a curved arm movable through the part which is secured to said casing and said arm being provided with a radial angular portion pivoted between said members, said casing and said arm being provided with guides which hold said arm against vertical or sagging movement.
2. A hinge comprising a part adapted to be secured to a door frame, a part adapted to be secured to a door, and a part detachably secured to the part adapted to be secured to the door frame, said last named part being provided with members which extend into the part which is adapted to be secured to the door frame, and the part which is adapted to be secured to the door being provided with a curved arm movable through the part which is secured to the part which is adapted to be secured to the door frame, and which is secured to the part which is adapted to be secured to the door frame, and which is provided with a radial angular portion pivoted between said members, the part which is adapted to be secured to the door frame and said arm being provided with interlocking guides which hold said arm against vertical or sagging movement, consisting of pins connected with one of said parts and curved surfaces in the other and over or around which said pins are movable.

said arm being provided with interlocking guides which hold said arm against vertical or sagging movement.

3. A hinge comprising a part adapted to be secured to a door frame, a part adapted to be secured to a door, and a part detachably secured to the part adapted to be secured to the door frame, said last named part being provided with members which extend into the part which is adapted to be secured to the door frame, and the part which is adapted to be secured to the door being provided with a curved arm movable through the part which is secured to the part which is adapted to be secured to the door frame, and which is provided with a radial angular portion pivoted between said members, the part which is adapted to be secured to the door frame and said arm being provided with interlocking guides which hold said arm against vertical or sagging movement, consisting of pins connected with one of said parts and curved surfaces in the other and over or around which said pins are movable.

In testimony that we claim the foregoing as our invention we have signed our names in presence of the subscribing witnesses this 27th day of February 1913.

CHARLES J. SOSS.
